To all whom it may concern:

Be it known that I, Edward E. Mecus, a citizen of the United States, residing in Milwaukee, in the county of Milwaukee and State of Wisconsin, have invented a new, original, and ornamental Design for a Shadow Box, of which the following is a specification, reference being had to the accompanying drawing, forming a part thereof.

Figure 1 is a front elevational view of a shadow box, showing my new design;

Figure 2 is a view in side elevation thereof; and

Figure 3 is a top plan view of the shadow box shown in Fig. 1.

Fig. 4 is a perspective view of the shadow box.

Portions of the drawing are lined to indicate a straited or irregularly grooved surface.

I claim:

The ornamental design for a shadow box, substantially as shown and described.
